[57] CLAIM

The ornamental design for a safety guard for a knife, as shown and described.

DESCRIPTION

FIG. 1 is a perspective view of a safety guard for a knife showing my new design;
FIG. 2 is a side view of the same safety guard, the opposite side view being a mirror image thereof;
FIG. 3 is an end view of the same safety guard, the opposite end view being a mirror image thereof;
FIG. 4 is a top view of the same safety guard;
FIG. 5 is an underside view of the same safety guard; and,
FIG. 6 and 7 are similar end views of the same safety guard, the broken line showings are for illustrative purposes only and forms no part of the claimed design.
